[57] CLAIM

The ornamental design for a paint pad holder, as shown and described.

DESCRIPTION

FIG. 1 is a perspective view;

FIG. 2 is a top plan view;

FIG. 3 is front elevational view; and,

FIG. 4 is a section view taken along line 4—4 of FIG. 2.

The broken line showing of a pad is for illustrative purposes only and forms no part of the claimed design.
